FRAMING MECHANISM

Augusto Dina, New York, N. Y.

Application December 20, 1930, Serial No. 503,681

3 Claims. (Cl. 88—17)

The invention relates broadly to motion imparting and translating devices, and more particularly to an improved adjusting means adapted for employment in operating the framing mechanism of a motion picture apparatus.

This invention is described and illustrated as part and for the purposes of imparting the required movement to the framing mechanism of a motion picture projector, such, for instance, as the framing mechanism described and claimed in my application, Serial No. 31,415, filed May 19, 1925, Patent No. 1,746,385, though the present invention finds a wide field of utility for other purposes. This application is a continuation in part of my Patent No. 1,746,385 issued February 11, 1930.

The principal objects and advantages of this invention reside in the provision of an improved motion imparting mechanism characterized by the provision of means for obtaining a predetermined displacement of certain elements with a minimum displacement of certain other elements; the provision of an improved means for operating the framing mechanism of a motion picture projector; the provision of an improved means for operating the framing and shutter compensating mechanisms of a motion picture projector; the provision of an improved lever operating mechanism; the provision of an improved means of the character described, which is interchangeable with various mechanisms; and the provision of an improved means for translating or transmitting motion of predetermined extent to an element and including motion reducing means.

This invention is further characterized by the provision of means in a motion picture projection apparatus for operating the framing and shutter compensating mechanisms from the rear of the machine so that this operation may be conveniently performed by the operator; the provision of a mechanism of the character referred to wherein the moving parts thereof are operable to a large degree in one vertical plane, thus reducing the space taken up by the framing apparatus.

The foregoing and such further objects and advantages as may appear or be pointed out as this description proceeds are attained in the structural embodiment illustrated in the accompanying drawing; in which:

The figure is a fragmentary elevational view, illustrating my invention applied to a prior art device, that is, to the frame, and oil box of a motion picture projector.

Referring now to the figure, which is in part a

form of prior art structure illustrated more in detail in the parent application, the conventional frame is shown at 45 upon which the oil box 14a is rotatably mounted about a shaft 15a, the oil box and said shaft being rotated by this invention which includes a gear 46 mounted upon the shaft 15a and meshing with an idler pinion 47 rotatably mounted on a shaft 48 secured to a frame 45 of the machine. 5

Motion is imparted to the pinion 47 by the provision of a segment 49 having its teeth 50 meshing with said pinion, said segment 49 being fixedly mounted, by the provision of screws 51, upon an arcuate laterally extending arm 52 integrally formed on the actuating lever 53. The actuating lever 53 is mounted at its inner end upon a fulcrum 54, and at its outer end is provided with a socket 55 for receiving an actuating handle 56 by which said lever 53 may be manipulated about its fulcrum to displace the segment 49 and thus impart rotation to the pinion 47 and gear 46. This operation serves to rotate the oil box and the parts of the Geneva gear movement contained therein for framing the picture.

The lever 53 is provided with a downwardly extending lug 57, which is pivotally connected to the lower end of the oscillatable lever 37a, pivoted at 38a and connected to a spiral pinion 21a engaging a worm 19a. This mechanism operates the shutter (not shown) in unison with the framing mechanism and is fully set forth in Patent No. 1,746,385 referred to.

The lever 37a performs the operation of synchronizing the shutter and is connected at 38b to the spiral pinion 21a, which in turn imparts 35 a partial rotation to the worm 19a mounted on the shutter shaft.

From the foregoing, it will be observed that in the invention herein disclosed the necessary motion of the lever 56 in order to rotate the gear 40 box is reduced to a minimum, due to the relatively greater radius of the gear segment 49 as compared with that of the gear 46.

Having thus described my invention and illustrated its use, what I claim as new and desire 45 to secure by Letters Patent is:—

1. In a framing mechanism, in combination, a supporting frame, a rotatable framing member including a gear, and mounted on said frame, means for displacing said rotatable framing member comprising a lever provided with a gear segment pivoted at one end on said frame and a pinion wheel mounted on said frame operatively connecting the gear segment of said lever with the gear of said rotatable framing member. 55

2. In a framing mechanism, in combination, a supporting frame, a rotatable framing member mounted on said frame, an operating lever pivoted at one end on said frame and a gear
- 5 train for operatively connecting said rotatable framing member and said lever, including a gear segment carried by said operating lever and a gear carried by said rotatable framing member, the gear segment of said lever having such a relation to the gear of said rotatable framing member that a given angular displacement of said lever will cause a relatively greater angular displacement of said rotatable framing member.
- 10 3. In a framing mechanism, in combination, a supporting frame, a rotatable framing member mounted on said frame, an operating lever pivoted at one end on said frame and a gear
- 15

train for operatively connecting said rotatable framing member and said lever comprising a segmental gear secured to a laterally extending arm of said operating lever and centered on the pivot of said operating lever, a toothed wheel secured to said rotatable framing member and centered on the axis of said rotatable framing member, and a pinion mounted on said supporting frame and permanently engaging said segmental gear and said toothed wheel, the gear ratio of said segmental gear and said toothed wheel being such that a relatively greater angular displacement of said rotatable framing member is secured by a given angular displacement of said lever.
